US00D973079S

(12) **United States Design Patent** (10) Patent No.: **US D973,079 S**
Matsumoto et al. (45) Date of Patent: **** Dec. 20, 2022**

(54) **DISPLAY SCREEN WITH GRAPHICAL USER INTERFACE**(71) Applicant: **Google LLC**, Mountain View, CA (US)(72) Inventors: **Masumi Matsumoto**, Kirkland, WA (US); **Adam Rodriguez**, Singapore (SG); **Thomas Horn**, Singapore (SG); **Bin Zhu**, Norcross, GA (US); **Xiaowen Karen Zhang**, Singapore (SG); **Yohan Launay**, Singapore (SG)(73) Assignee: **Google LLC**, Mountain View, CA (US)(**) Term: **15 Years**(21) Appl. No.: **29/765,704**(22) Filed: **Jan. 11, 2021****Related U.S. Application Data**

(60) Division of application No. 29/701,890, filed on Aug. 15, 2019, now Pat. No. Des. 910,057, which is a continuation of application No. 29/622,346, filed on Oct. 17, 2017, now abandoned.

(57) **CLAIM**

The ornamental design for a display screen with graphical user interface, as shown and described.

DESCRIPTION

The FIGURE is a front view of a display screen with graphical user interface showing our new design.

The dot-dash line showing of a display screen forms no part of the claimed design. The remaining even broken lines show portions of the graphical user interface that form no part of the claimed design.
